UNITED STATES PATENT OFFICE.

GEORGE H. F. HOLY, OF PITTSBURGH, PENNSYLVANIA, ASSIGNOR TO WESTINGHOUSE ELECTRIC & MANUFACTURING COMPANY, A CORPORATION OF PENNSYLVANIA.

DRIVING CONNECTION FOR LOCOMOTIVES.

Application filed March 23, 1921. Serial No. 454,687.

To all whom it may concern:

Be it known that I, GEORGE H. F. HOLY, a citizen of the United States, and a resident of Pittsburgh, in the county of Allegheny and State of Pennsylvania, have invented a new and useful Improvement in Driving Connections for Locomotives, of which the following is a specification.

My invention relates to driving connections for electric locomotives and particularly to means for the transmission of power from the motor to the driving wheels.

The object of my invention is to eliminate certain strains to which driving connections of the types commonly employed are subjected, through the rise and fall of the driving wheels on the one side of the locomotive relatively to those on the other side thereof.

A further object is the provision of an intermediate driving member of such construction and so mounted as to eliminate the driving strains usually placed on the jack shaft, or other intermediate drive, under ordinary driving conditions.

Still another object is the provision of a construction wherein the intermediate driving member may be readily removed from the locomotive.

In an electric locomotive of that type wherein the motor drives the traction wheels through pinions, jack-shaft gear and side rods, it is usual to extend the jack shaft clear across the locomotive and to mount a gear on each end thereof in position to be driven by one of the motor pinions. These gears carry crank pins to which the side rods for driving the traction wheels are connected.

The jack shaft is supported on the frame, and, as the driving wheels are supported directly by the rails, relative vertical movement takes place between the driving wheels and the gears on the jack shaft. This results in a tendency to vary the distance between the crank pins to which the side rods are connected as the driving wheels encounter irregularities in the surface of the rails. However, since the connection between the driving wheels and the intermediate gears is rigid, the jack shaft is caused to rotate sufficiently to compensate for the relative vertical movement between the driving wheels and the intermediate gear. This movement is, of course, transmitted to the intermediate gear that is on the other end

of the jack shaft. This action results in a strain being thrown upon said other gear, especially when the rotative compensating movement that is imparted thereto is in a direction opposite to that in which the gear 60 happens to be rotating.

Instead of mounting a pair of intermediate gears on a single jack shaft, I mount each gear independently of the other, except that they may mesh with pinions that are 65 mounted on a single motor shaft. The intermediate gears are of the resilient type and, consequently, any irregularities of movement by one of the driving wheels and its associated intermediate gear are absorbed 70 by the resilient elements instead of being transmitted to the intermediate gear at the other side of the locomotive.

My construction possesses the further advantage of leaving clear that space between 75 the sides of the locomotive frame which was formerly occupied by the jack shaft.

Referring now to the accompanying drawings:

Figure 1 is a side elevational view of a 80 portion of a locomotive with my invention applied thereto;

Fig. 2 is a plan view of the same, with the locomotive cab removed, and

Figs. 3 and 4 are views, similar to those 85 of Figs. 1 and 2, but illustrating a modification of my invention.

A locomotive cab 5 is supported, in the usual manner, upon side frames 6 and 7 that are, in turn, supported in any desired 90 manner by driving wheels 8, 9, 10 and 11, and a usual pony truck 12.

A pair of motors 13 and 14 are mounted on the side frames 6 and 7 and are provided with shafts 15 and 16, respectively, 95 on which are mounted pinions for transmitting the power from the motors. The motors operate in the usual manner, and a description of one of them, with relation to the driving mechanism, will suffice for 100 both.

A pair of pinions 17 and 18, which are secured to the shaft 15, mesh with gear wheels 19 and 20, respectively, and operate through them to drive side rods 21 and 22 105 to which the traction wheels 8 and 9 are connected.

The gear wheels 19 and 20 are each of the resilient type and consist of a gear rim 23 and a gear center 24, between which 110

spring elements 25 are interposed to provide flexibility between the gear centers and the gear rims.

The gear centers form parts of crank shafts 26 and 27 that are respectively mounted in bearings 28 in the side frames, and bearings 29 formed in bearing brackets 30 that are laterally disposed with respect to the side frames 6 and 7. A pair of crank pins 31 and 32 serve to rigidly connect the portions of the crank shafts and to pivotally support one end of the side rods 21 and 22, respectively.

In the form of construction illustrated in Fig. 2, the bearing brackets 30 consist of lugs 33 and 34, formed integrally with the side frames 6 and 7, respectively, and extension members fastened thereto by means of bolts 35. Removal of the bolts 35 permits the bearing brackets to be disassembled and permits of the ready removal of the crank shafts 26 and 27 and the gear wheels 19 and 20 carried thereby. The portions 27 of the crank shafts are formed with extensions 36 that serve to counterbalance the weight of the crank pins and the ends of the side rods 21 and 22 which are supported thereon.

The rotation of the motors is imparted, through the pinions and the intermediate gear wheels 19 and 20, to the side rods 22, and the resilient elements function in the manner common in drives of this character. If, for instance, the driving wheel 9 should encounter an irregularity in the surface of the rail, the tendency would be to suddenly vary the normal distance between its crank pin and the crank pin 32 of the crank shaft, but, due to the flexibility between the crank shaft and the gear rim, this tendency to irregularity of movement is compensated for and is not transmitted to the crank pin 31 at the other side of the locomotive, as would be the case were the gear centers 24 mounted on a single jack shaft.

It will be further observed that, instead of driving strains being imposed on the crank shaft at a point outside its bearings, as in the case of the ordinary jack shaft drive, such strains are imposed on the shaft at a point intermediate the two bearings that support said shaft and there is, consequently, no tendency to bind the shaft in its bearings.

The modified construction illustrated in Figs. 3 and 4 is the same as that just described in connection with Figs. 1 and 2, with the exception that the bearing brackets 30 are of one piece and formed integrally with the side frames 6 and 7. The bearings 29 are open at the bottom, as illustrated in Fig. 3, and are provided with a closure member 37 which is secured to the bearing by means of bolts 38.

To remove the crank shaft, it is simply

necessary to take off the member 37 and allow the end of the crank shaft to fall out of this bearing, after which it can be readily slid out of the bearing 28.

If desired, the pinions which are mounted upon the ends of the motor shafts may be of the flexible gear type, that is, they may comprise a toothed rim portion and a hub or center portion, with flexible elements interposed therebetween, to secure resilient driving action, as in the case of the gear wheels 19 and 20.

Various other modifications may be made in the construction without departing from the spirit of the invention, as set forth in the appended claims.

I claim as my invention:

1. In combination, in a locomotive driving mechanism, a motor-driven shaft extending transversely of the locomotive frame and having pinions mounted on each end thereof, and gears mounted adjacent to the said shaft and meshing with each of the pinions, said gears being mounted independently of one another, and having flexible connection with the traction wheels of the locomotive.

2. In combination, a locomotive driving mechanism, a motor-driven shaft extending transversely of the locomotive frame, a pinion on each end of said shaft, a gear meshing with each of the pinions and comprising a gear rim and a gear center for supporting the gear rim, a yielding driving element between the gear rim and the gear center, a crank adapted to be driven by the gear center, and side rods connecting said crank with the locomotive traction wheels, the crank being supported from a bearing located exteriorly of the side frames of the locomotive.

3. A locomotive drive comprising a motor, a motor shaft provided with a pinion on each of its ends and extending transversely of a locomotive frame, a gear meshing with each pinion and mounted on a shaft that is supported exteriorly of the side frames of the locomotive.

4. A locomotive drive comprising, in combination, a driving member provided with oppositely disposed pinions located exteriorly of the side frames of the locomotive, and driving members meshing with each of said pinions and mounted independently of each other.

5. In combination, a driven mechanism, a driving shaft provided with a pinion on each end thereof, an intermediate gear meshing with each of said pinions, said gears being independently mounted and comprising a gear rim and a gear center with flexible connections therebetween, and driven members connected to each of the gear centers.

6. In combination, in a driving mechanism, a pair of pinions, a pair of driven gears mounted independently of each

other and each meshing with a pinion, a crank shaft driven by each of the gears, and a flexible connection between the crank shafts and the pinion.

5 7. In combination, in a driving mechanism, a pair of driving members, a pair of intermediate driven members mounted independently of each other, main driven members connected to the intermediate 10 driven members and flexible driving connections interposed between the driving members and the driven members.

8. In combination, in a locomotive driving mechanism, a driving shaft extending 15 transversely of the locomotive frame and

having a pinion mounted on each end thereof, and gears meshing with each of the pinions, said gears being mounted on separate axles and one of them being flexible.

9. A gear support for a locomotive comprising a bearing located in one longitudinal side of the frame and a bearing located in a lug carried on the locomotive frame and extending laterally and longitudinally to a point opposite the first main bearing. 20 25

In testimony whereof, I have hereunto subscribed my name this 28th day of February, 1921.

GEORGE H. F. HOLY.
